Primary Examiner — Christy Nemeth*Assistant Examiner* — Leah E Hoeferkamp(74) *Attorney, Agent, or Firm* — Notaro, Michalos & Zaccaria P.C.(57) **CLAIM**

The ornamental design for an industrial computer, as shown and described.

DESCRIPTION

FIG. 1 is a front elevational view of an industrial computer of our new design;

FIG. 2 is a back side elevational view thereof;

FIG. 3 is a front, left, top perspective view thereof;

FIG. 4 is a left side elevational view thereof;

FIG. 5 is a top plan view thereof;

FIG. 6 is a right side elevational view thereof;

FIG. 7 is a bottom plan view thereof; and,

FIG. 8 is a back, left, top perspective view thereof.

The broken lines illustrate portions of the article that form no part of the claimed design.

1 Claim, 8 Drawing Sheets(56)
